SHEET METAL SHEARS WITH LINKAGE

Claude B. Garland, Compton, Calif., assignor of
one-half to Carl Frye, Long Beach, Calif.

Application February 5, 1951, Serial No. 209,335

3 Claims. (Cl. 30—242)

1

This invention relates to a sheet metal shears, and particularly a sheet metal shears adapted for manual operation.

In the conventional hand operated sheet metal shears popularly known as "tin-snips" two lever arms are pivoted to each other at a common transverse fulcrum axis, which is usually located substantially nearer one end of the levers than the other end thereof. The longer ends of the levers are provided with hand grips and the shorter ends with cutting edges, which as the levers move about their common fulcrum axis move toward and away from each other in a cutting plane perpendicular to the work sheet. In order to accomplish a traveling cut from the fulcrum axis outwardly of the work sheet, tin snips are of the scissors type of shearing tool, i. e., the fulcrum axis is offset inwardly with respect to the line of the cutting edge of at least one of the levers, for if the fulcrum axis were aligned with both cutting edges, these edges would contact each other simultaneously at all points of their length. The tool would then not be of the scissors type, but would be of the pliers type and would require the application of an excessive squeezing pressure to effect a cut of the work sheet the entire length of the cutting edges at one instant.

As the application of this excessive pressure is impractical for hand operated shears, the two levers of the tin snips are of necessity given the relative position of the two blades of a pair of scissors.

Tin snips, i. e., scissors type shears, have inherent disadvantages, due to the pivotal connection of the blades and the consequent relative arcuate travel of these blades. As the metal sheet is cut, the two severed portions of the sheet, as the point of severance travels across the sheet, must move vertically away from each other, being bent and directed away from each other by the metal of the body of the levers to the rear of the cutting edges and around the hubs of the fulcrum pivotal connection and extending back to the handles. By the very nature of the construction of snips or scissors, it is difficult to provide a throat to receive the severed sheet portions rearwardly of the cutting edges without bending them excessively as the snips travel forwardly of the sheet. This disadvantage becomes serious in the case of relatively thick sheets of metal which resist this bending action, limiting the field of use of tin snips. It is also difficult to provide for the handling particularly of the upwardly curving severed por-

2

tion of the sheet to the rear of the cut, which tends as its length increases to drop downwardly of its weight in a reverse curve, requiring more manual pressure to effect the cut and making it more difficult for the operator to follow a straight line in making the cut.

Tin snips tend to stretch the metal at the cutting point, due to the vertical divergence of the two severed portions of the sheet, preventing a smooth, clean cut. Furthermore, the cutting angle between any two pivoted blades decreases as the blades pass each other, speeding up the travel of the point of severance, making it necessary to apply increasing pressure to the handles as the cutting angle decreases. Also at the beginning of the movement of the blades toward each other, the cutting angle is so great that an undue component of the force applied by the operator is lost in pushing the cutting blades longitudinally of the sheet as compared to the pressure effectively applied transversely of the sheet to sever it.

If the blades of a hand operated metal shears are so mounted as to approach each other for the cutting operation, in a relatively rectilinear manner, such as characterizes power operated square metal shears, the above disadvantages of pivotally mounted blades will be obviated. And if the cutting edges of these relatively rectilinearly traveling blades are slightly inclined relative to each other, the advantages of the low power of a traveling cut will be realized.

It is one object of this invention to provide a hand operated metal shears in which the cutting blades shall have a relative rectilinear cutting movement toward and away from each other.

It is another object to provide a hand operated metal shears in which the two severed sheet portions may travel rearwardly from the point of severance with a minimum of bending from the plane of the unsevered sheet.

It is another object to provide a hand operated metal shears in which the applied power shall be relatively light and shall be constant throughout the length of the cut for each successive position of the shears along the sheet.

It is another object to provide a hand operated metal shears of compact construction, reliable in its operation, which shall make a clean smooth cut without deforming the work sheet, and with a minimum of effort by the operator.

In the drawings,

Figure 1 is a side elevation of a metal shears embodying the invention;

Figure 2 is a top plan view of the shears;

Figure 3 is a sectional view taken as indicated by the line 3—3 of Figure 1;

Figure 4 is a sectional view taken along the line 4—4 of Figure 1.

The shears comprises a lower cutting blade 15, an upper blade 12, handles 13 and 14 for the blades 15 and 12, respectively, and the several devices to be presently described for connecting the blades for relative rectilinear movement, and for connecting the handles to the blades.

The blade 15 and handle 13 are rigidly related and are preferably portions of a single forging in the general form of a horizontally disposed yoke 11 open at its leftward end as seen in Figure 1, for the reception of the work sheet. The lower leg of the yoke 11 constitutes the lower blade 15 of the shears, having a cutting edge 16. The upper blade 12 has a cutting edge 25 formed preferably on a replaceable inset 25'. The upper leg 17 of the yoke 11 is the leftward end portion of the handle 13 and is laterally offset from the blade 15, the left face of the upper leg as seen in Figures 3 and 4 being substantially coincident with the right face of the blade 15. The two legs are connected by a neck 18. The neck and adjoining parts of the yoke are shaped to provide an upwardly facing, generally horizontal surface 19 upon which the one portion of the severed sheet rests, and a downwardly facing generally horizontal surface 20 against which the other portion of the severed sheet bears upwardly. The surfaces 19 and 20 are not quite parallel but form an acute angled edge 21 at their forward ends and very gradually diverge rearwardly extending to the rear face of the neck 18.

The two portions of the severed sheet move rearwardly over these surfaces and are slightly bent apart at the edge 21, being separated as they leave the shears by a vertical spacing equal to the depth of the distance between the rear ends of the surfaces 19 and 20. If the work sheet is supported by a work table during the shearing operation, the slight bending of the sheet as it rises to enter the opening between the blades, and the further slight bending of the severed-sheet portions, first at the edge 21, and later as they drop toward and onto the table as they leave the shears, offers no real difficulties in performing the cutting operation.

The upper leg 17 of the yoke 11 overlies the upper blade 12. It has two parallel vertical bores 22 overlying the two end portions of the blade 12, respectively, which slidably receive the two pins 23 and 24. These pins at their lower ends are rigidly secured to the blade 12, as by a pressed fit, a threaded connection or in other suitable fashion. The blade 12 will then of necessity travel in straight lines with respect to blade 15. The blade 12 is mounted on the pins 23 and 24 with its cutting edge 25 at a small acute angle α to the cutting edge 16 of the blade 15 so as to effect a traveling cut of the work sheet between them requiring a relatively small thrust force between the blades. The cutting angle α between the blades remains constant from one end of the cut to the other, with the result that the cutting pressure is also constant.

The handle 14 is connected to the blade 12 by a linkage system arranged to apply thrusts of equal value to the pins 23 and 24 as they are held to their parallel travel transversely of the leg 17. The handle 14 is forked at 26, the two arms 27 and 28 of the fork receiving between them the flattened upper end 29 of pin 24, the upper end 30' of a vertical link 30, and the right-

ward end of a horizontal link 31. Pins 32, 33 and 34 establish pivotal connections between the two arms of the handle fork on the one hand and the pin 24, link 30 and link 31, respectively.

5 The upper end 23' of blade pin 23 is forked to receive the leftward end of horizontal link 31, and is pivotally connected thereto by a pin 43. The lower end of the vertical link 30 depending from the handle 14, and the lower end of a second 10 similar vertical link 35 are seated in slotted recesses 36 and 37 in the upper portion of the leg 17, and are pivotally connected to the leg 17 by pins 38 and 39, respectively, which span these recesses. The upper end 35' of the link 35 is 15 forked, the branches of the fork embracing the link 31, which is pivotally connected thereto by a pin 40.

Grips 41 and 42 formed on the rightward ends of the handles 13 and 14 respectively enable the 20 operator to grasp the handles between the thumb and fingers of one hand and urges the handles toward each other with a squeezing pressure. As the handle 14 moves downwardly, it rocks on pivot pin 33, moving the blade pin 24 and rightward end of the blade 12 straight downwardly. Assuming that the lower blade 15 and its handle 13 are stationary, and the blade holding pins 23 and 24 are in a vertical position, for clarity of 25 description of the relative movement of the parts 30 of the shears, then, as the handle 14 descends, the blade pin 24 will move vertically downward, and with it the pivot pin 32 at its upper end.

It is then apparent that the pivot pin 33 will 35 have a slight arcuate movement about pivot pin 33 as a center and toward the pivot pin 32, and the pivot pin 34 will move upwardly a distance about equal to the downward movement of blade holding pin 24, but will also be pulled a slight distance to the right of its initial position. The 40 leftward end of link 31 will be similarly rocked on pivot pin 40 which will move arcuately a slight distance toward pivot pin 41 as this pin 41 forces the blade pin 23 and the leftward end of blade 12 vertically downward a distance equal to the vertical downward movement of blade pin 24 and the rightward end of blade 12. The pin bearing opening 44 in the rightward end of link 31 is in the form of a slot, being elongated horizontally to permit the handle 14 and the link 31 45 to move apart sufficiently to accommodate the arcuate movements of the pins 33 and 40 to and from each other as the tool is operated. The vertical width of this slot is such that the pivot pin 34 snugly fits between its top and bottom walls.

50 55 A biasing spring 45 is seated operatively between the end 29 of blade pin 24 and the yoke leg 17 to hold the handles 13 and 14, and blades 12 and 15 normally in open position as determined by a stop 46 between blade 12 and yoke legs 17.

The essential condition of the disposition of the linkage connecting the handle 14 to the blade pins 23 and 24 is that the links 30 and 35, their 60 pivoting axes at each end, and the pivoting axes of the pins 32, 34 and 41 be symmetrically related to an imaginary plane parallel to the blade pins 23 and 24 and in which lies the axis of pivot pin 34.

65 70 In the operation of the shears, the tool is placed on one edge of the work sheet with the sheet in position between the blades 12 and 15. The handles 13 and 14 are manually operated to cause the cutting blades to make successive cuts, the two portions of the severed work sheet

diverging vertically at a slight angle at 21, with a minimum of bending of the metal. The manual pressure exerted is constant throughout the length of the cut made in each successive position of the tool on the work sheet. The tool can therefore be designed to use a practical maximum manual pressure during the entire cutting operation. The inherent limitations of the conventional shears require that it be designed to use a cutting pressure substantially less than the practical maximum manual pressure, since this maximum pressure must be reserved for use at those short portions of the travel of the point of severance which require a greater than average pressure.

This invention adapts the principle and advantages of the relatively rectilinearly moving cutting blades of square shears to manual handle-operated shears, to provide a use at maximum efficiency of manual pressure.

I claim:

1. In a sheet metal cutter, the combination of: a horizontally disposed forwardly opening yoke shaped first member, having a first handle extending rearwardly therefrom with a manual grip at the rear end, the said first member having an upper leg and a lower leg, said lower leg having an elongated cutting edge; a second member having an elongated cutting edge; a first link pivotally connected to the upper leg and extending upwardly therefrom; a rearwardly extending first lever medianly fulcrumed to the outer end of the first link and having a manual grip at its rear end and formed with a longitudinally extending slot at its front end; a second link of the same effective length as the first link and pivotally connected to the upper leg in front of said first link and extending outwardly from the upper leg; a second lever medianly fulcrumed to the outer end of the second link and formed with an opening at its rear end cooperatively related to said slot to receive a hinge pin; a hinge pin seated in said slot and opening; and a pair of upwardly directed parallel rigid extensions of said second member slidably engaging said upper leg, the rearward of said extensions being pivotally connected to said first lever to the rear of said first link and the forward of said extensions being pivotally connected to the second lever in front of said second link, said links, extensions and pivotal connections of said links and extensions being symmetrically related to a plane parallel to the said extensions and embracing the axis of the hinge pin connection between said levers, and the extensions, links, levers and legs being dimensioned and related to dispose the cutting edges for shearing engagement at a small forwardly opening acute angle.

2. In a sheet metal cutter, the combination of: a first member having an elongated cutting edge; a second member having a second elongated cutting edge; a first straight pin rigidly secured to said second member adjacent one end

of the cutting edge thereof; a second straight pin rigidly secured to said second member adjacent the other end thereof and parallel to said first pin; said second member being provided with two straight line parallel guideways for engaging said pins respectively, said pins and guideways being disposed to position one cutting edge at a slight acute angle to the other cutting edge and to constrain relative movement of the two members in a direction transverse to a work sheet in shearing position between said cutting edges; a lever pivoted to the outer end of one of said pins on a first axis; a lever extension pivoted at one end to the inner end of said lever on a second axis and at the other end to the outer end of the other pin on a third axis; a first link pivoted at its outer end to said lever on a fourth axis between said first and second axes and at its inner end to said first member on a fifth axis; a second link pivoted at its outer end to said lever extension on a sixth axis between said second and third axes and at its inner end to said first member on a seventh axis, said seven axes, and said first and second links being symmetrically related to a plane passing through said second axis and parallel to said pins, and the lever and lever extension being formed at their pivotal connection to permit relative longitudinal movement; and means for applying a thrust to the outer end of the lever toward the plane of the work sheet.

3. In a sheet metal cutter, the combination of: a yoke having an upper leg and a lower leg; a first handle on the yoke; an upwardly directed first cutting blade on the lower leg; a downwardly directed second cutting blade; a first holder mounted on the upper leg and rigidly connected to the end of the second blade to dispose the cutting edge of the second blade in cutting relation with the cutting edge of the first blade at a small forwardly opening acute angle thereto; a second holder rigidly connected to the front end of the second blade and slidably mounted on the upper leg for movement parallel to the movement of the first holder; a second handle pivotally connected to the outer end of the first holder to dispose the outer end of the handle in position for manual gripping relation with the first handle; and linkage connecting the forward end of the second handle to the upper leg and to the upper end of the second holder dimensioned and related to convert movement of the second handle toward the first handle into movements of the same magnitude of the two holders respectively.
